UNITED STATES PATENT OFFICE.

JOHN DOYLE, OF HOBOKEN, NEW JERSEY.

DESIGN FOR A KITE.

SPECIFICATION forming part of Design No. 31,724, dated October 24, 1899.

Application filed September 27, 1899. Serial No. 731,878. Term of patent 7 years.

To all whom it may concern:

Be it known that I, JOHN DOYLE, a citizen of the United States, residing at Hoboken, Hudson county, State of New Jersey, have invented and produced a new and original Design for Kites, of which the following is a specification.

The leading feature of my design is a kite substantially as exhibited in the accompanying drawing, in which drawing, *a* represents

a substantially triangular or tapering sail, adjacent to which is located the substantially rectangular sail *b*.

I claim—

The design for a kite, substantially as herein shown and described.

JOHN DOYLE.
